(57) **CLAIM**

I claim the ornamental design for a pre-form with handle, as shown and described.

DESCRIPTION

FIG. 1 is a front-left perspective view of the pre-form with handle showing my new design;

FIG. 2 is a cross sectional view in the direction of line 2-2 of FIG. 1 thereof;

FIG. 3 is a cross sectional view in the direction of line 3-3 of FIG. 2 thereof; and,

FIG. 4 is a cross sectional view in the direction of line 4-4 of FIG. 2 thereof.
